UNITED STATES PATENT OFFICE.

CLYDE W. LANDERS, OF TACOMA, WASHINGTON.

BRAKE-BAND.

1,229,624.

Specification of Letters Patent. Patented June 12, 1917.

Application filed May 17, 1916. Serial No. 98,151.

To all whom it may concern:

Be it known that I, CLYDE W. LANDERS, a citizen of the United States, residing at Tacoma, in the county of Pierce and State 5 of Washington, have invented certain new and useful Improvements in Brake-Bands, of which the following is a specification.

My invention relates to improvements in brake bands, adapted for use in connection 10 with automobile constructions, while not necessarily restricted to such use.

An important object of the invention is to provide a brake band of the above mentioned character, so constructed that the 15 same will not have exclusive clamping or binding action with the drum, causing the wheels of the automobile to slip, and which will contact with the drum to properly reduce or stop its rotation.

20 A further object of the invention is to provide a brake band of the above mentioned character, which is adapted to retain itself properly lubricated, whereby it is highly durable.

25 A further object of the invention is to provide a brake band of the above mentioned character, which will possess a high degree of spring or elasticity.

30 A further object of the invention is to provide a brake band of the above mentioned character, having a fibrous lining held in place by metallic inserts or segments, which are held against improper turning or twisting movements.

35 Other objects and advantages of the invention will be apparent during the course of the following description.

In the accompanying drawings forming 40 a part of this specification and in which like numerals are employed to designate like parts throughout the same.

Figure 1 is a side elevation of a brake band embodying the invention.

Fig. 2 is a transverse sectional view taken 45 on line 2—2 of Fig. 1.

Fig. 3 is a perspective view of a metallic insert or segment, and,

Fig. 4 is a similar view of another metallic insert or segment.

50 In the drawings, wherein for the purpose of illustration is shown a preferred embodiment of my invention, the numeral 10 designates a resilient metallic band. Arranged upon the outer side of the band 10 adjacent its free ends, are attaching elements 11, secured thereto by any suitable means.

The band 10 is bent outwardly at preferably equidistantly spaced intervals providing outwardly bulging curved portions 12. Arranged upon the inner surface of the 60 band 10 is a strip of absorbent or fibrous material 13, which may be asbestos or any other suitable fabric. The strip 13 has outwardly bent portions 14, projecting into the outwardly bulging portions or pockets 12 65 of the band, as shown.

The numeral 15 designates metallic inserts or segments, preferably formed of bronze while other metal or material may be employed. Each insert 15 has an outer 70 curved surface 16, adapted to contact with the outwardly bent portion 14 of the fibrous strip 13. Each segment has an inner curved surface 16', which is substantially flush or continuous with the inner surface of the 75 strip 13. The insert 16 is provided with a trunnion or bolt 17, preferably rigidly secured thereto. This trunnion or bolt is adapted for insertion through openings formed in the strip 13 and the ring 12 and 80 its outer end is flattened or riveted for providing a head 18, as shown. The turning movement of the segment is prevented by means of a lug or projection 19, formed upon its side 16 which extends into a recess 85 20 formed in the strip 13.

The numeral 21 designates inserts or segments, preferably formed of bronze or other suitable material. These segments are arranged upon the ring 10 adjacent the attaching elements 11. Each segment is preferably of substantially the same thickness as the strip 13 and its inner surface is flush or continuous therewith, as shown. Each segment 21, shown in Fig. 3, is provided 90 with a trunnion or lug 22, adapted for insertion through openings formed in the band 10 and attaching member 11. The outer end of the trunnion or bolt 22 is flattened or riveted, providing a head 23, which serves 95 to attach the segment to the band. The turning movement of the segment is prevented by means of a lug or extension 24, projecting into an opening or recess formed in the band 10. The segments 21 do not 100 overlap the strip 13 but are arranged in end to end relation thereto.

From the foregoing description it is obvious, that during operation, the segments 15 and 21 may be brought into proper engagement with the drum, to retard its movement or stop the same. The drum operates 110

in oil and this oil is continuously fed to the segments 15 and 21 by the portions of the band 13 between the same, which band absorbs the oil, grease, or other lubricant.

5 It is to be understood that the form of my invention herewith shown and described is to be taken as a preferred example of the same, and that various changes in the shape, size, and arrangement of parts may be 10 sorted to without departing from the spirit of the invention or the scope of the subjoined claims.

Having thus described the invention, I claim:

- 15 1. In a device of the character described, a band having portions of its material bent outwardly at spaced intervals to form outwardly bulging pockets, a fibrous strip arranged upon the inner surface of the band
- 20 and having portions of its material bent outwardly at spaced intervals to fit within the outwardly bulging pockets, metallic

segments engaging the inner side of the outwardly bent portions of the fibrous strip, and means to attach the segments to the 25 band.

2. In a device of the character described, a band provided with outwardly bulging pockets arranged at spaced intervals, an absorbent strip disposed upon the inner surface of the band and having portions thereof projecting into the pockets, metallic segments engaging the strip adjacent the pockets and having their inner surfaces substantially flush with the inner surface of the 30 strip, and means to attach the segments to the band.

In testimony whereof I affix my signature in presence of two witnesses.

CLYDE W. LANDERS.

Witnesses:

H. H. BLACKBURN,
HELEN A. HARTMAN.
